CLAIM

The ornamental design for a body groomer handle as shown and described.

DESCRIPTION

FIG. 1 is a front, right, top perspective view of a body groomer handle, showing my new design;

FIG. 2 is a rear, left, bottom perspective view thereof;

FIG. 3 is a front elevational view of the reduced scale thereof;

FIG. 4 is a rear elevational view of the reduced scale thereof;

FIG. 5 is a left side view of the reduced scale thereof;

FIG. 6 is a right side view of the reduced scale thereof;

FIG. 7 is a top plan view of the enlarged scale thereof;

FIG. 8 is a bottom plan view of the enlarged scale thereof;

FIG. 9 is a front, right, top perspective view of its reduced scale thereof, indicating the usage environment;

FIG. 10 is a front, right, top perspective view of its reduced scale thereof, indicating the usage environment;

FIG. 11 is a front, right, top perspective view of its reduced scale thereof, indicating the usage environment;

FIG. 12 is a front, right, top perspective view of its reduced scale thereof, indicating the usage environment;

FIG. 13 is a front, right, top perspective view of its reduced scale thereof, indicating the usage environment;

FIG. 14 is a front, right, top perspective view of its reduced scale thereof, indicating the usage environment; and,

FIG. 15 is a front, right, top perspective view of its reduced scale thereof, indicating the usage environment.

The broken lines shown in FIGS. 1-7 illustrate portions of the body groomer handle and form no part of the claimed design. The broken lines shown in FIGS. 9-15 illustrate the environment of the body groomer handle and form no part of the claimed design.

1 Claim, 15 Drawing Sheets
